UNITED STATES PATENT OFFICE

153,784

DESIGN FOR A DISPLAY SIGN

Gilbert C. Gettelman, Hartford, Wis., assignor, by
mesne assignments, to Hamilton Watch Com-
pany, Lancaster, Pa., a corporation of Pennsyl-
vania

Application August 12, 1947, Serial No. 140,827

Term of patent 3½ years

(Cl. D1—12)

To all whom it may concern:

Be it known that I, Gilbert C. Gettelman, a citizen of the United States, residing at Hartford, in the county of Washington and State of Wisconsin, have invented a new, original, and ornamental Design for a Display Sign, of which the following is a specification, reference being had to the accompanying drawing, forming part thereof.

Figure 1 is a front elevation of the display sign showing my new design.

Figure 2 is a top plan view of the same.

Figure 3 is an end view of the same.

The dominant features of my design reside in the portion shown in full lines.

I claim:

The ornamental design for a display sign, as shown and described.

GILBERT C. GETTELMAN.
